CLAIM

The ornamental design for a tooth cleaning device, as shown and described herein.

DESCRIPTION

FIG. 1 is a front, top, right side perspective view of a tooth cleaning device in accordance with another embodiment of the present design.

FIG. 2 is a front, bottom, right side perspective view of the tooth cleaning device shown in FIG. 1.

FIG. 3 is a front plan view of the tooth cleaning device shown in FIG. 1.

FIG. 4 is a rear plan view of the tooth cleaning device shown in FIG. 1.

FIG. 5 is a left side plan view of the tooth cleaning device shown in FIG. 1.

FIG. 6 is a right side plan view of the tooth cleaning device shown in FIG. 1.

FIG. 7 is a top plan view of the tooth cleaning device shown in FIG. 1; and,

FIG. 8 is a bottom plan view of the tooth cleaning device shown in FIG. 1.

The broken lines in the figures illustrate portions of the article which form no part of the claimed design.

1 Claim, 5 Drawing Sheets
